UNITED STATES PATENT OFFICE

WILLIAM E. WOODARD, OF FOREST HILLS, NEW YORK

LIMITED CUT-OFF LOCOMOTIVE AND METHOD OF OPERATION

Application filed January 7, 1927. Serial No. 159,618.

This invention relates to locomotives and particularly to that type which has now become known in the art as a limited cut-off locomotive. It also involves a new method of operating a locomotive.

The nature and objects of the invention will be more clearly understood and appreciated if the following facts are kept in mind. It is a well recognized fact that if the maximum cut-off is limited to a point which is substantially less than normal, a pronounced saving in steam consumption can be effected per unit of work. For instance in heavy freight service with a locomotive limited to a 60% maximum cut-off there is in the neighborhood of a 20 to 25% saving in steam consumption as compared with former practice where the average normal maximum cut-off was around 85%. It follows that the shorter the maximum cut-off can be made the greater will be the saving because of the greater expansive use of the steam.

However, with the arrangements heretofore relied upon it is not practicable to set the maximum cut-off below a well defined limit because of the fact that the engine may stop with the cranks in such positions as will prevent the entry of steam to the cylinders at starting or, if admitted, will reduce the turning moment to such an extent that it will not be sufficient to get the engine in motion.

With the customary valve arrangements met with in standard practice where there is no particular method of delivering steam to the cylinders at these disadvantageous positions of the crank, 70% maximum cut-off is about the lowest limit which can be used. Furthermore, with the auxiliary port arrangement disclosed in the patent to Kiesel No. 1,307,821 it has been demonstrated by experience that a 60% maximum cut-off is about the lowest that it is possible to use and still have a locomotive which will start in all positions of the crank. But, as already pointed out, it is highly desirable to use even shorter maximum cut-offs than the foregoing and it is the principal object of my invention to provide means for limiting the maximum cut-off to any desired point while at the same time providing for sure and prompt starting

of the locomotive at any position of the cranks.

It is also an object of my invention to provide, in a limited cut-off locomotive, a means for automatically lengthening the cut-off when starting the locomotive and subsequently returning it automatically to the predetermined limited maximum cut-off.

A further object of the invention resides in the provision of means for subjecting or subordinating the said automatic features to the control of the pressure in the locomotive steam chests in connection with which I arrange for the lengthened cut-off until such time as the steam chest pressure rises to a predetermined point.

Still another object of the invention is to make the foregoing automatic apparatus subordinate to the position of the reverse gear or some moving part associated therewith. In other words I provide for an arrangement of the parts whereby the lengthened cut-off is possible only when in a maximum limited cut-off position.

I also propose a method of operating a limited cut-off locomotive which involves lengthening the cut-off beyond the predetermined limit whenever the steam chest pressure is below a certain predetermined standard but returning it to the limit when said pressure is above said standard.

My invention also contemplates the provision of means for and the operation of a locomotive whereby the cut-off will be lengthened automatically when the steam chest pressure is below a predetermined standard and subsequently shortened should the pressure rise above said standard.

The foregoing together with such other objects as are incident to my invention or which may appear hereinafter are obtained by means of a construction which is illustrated in preferred form in the accompanying drawings, wherein

Fig. 1 is a side elevation of a locomotive with my invention applied thereto;

Fig. 1a is a view similar to that of Fig. 1 but showing only the principal parts of my invention in a purely diagrammatic manner;

Fig. 2 is an enlarged side elevation of a part

of the apparatus utilized in carrying out my invention with certain portions illustrated in section;

Fig. 2a is a fragmentary view of a portion of the structure shown in Fig. 2 but illustrating a modified arrangement of the parts to be described hereinafter.

Fig. 3 is a section on the line 3—3 of Fig. 2;

10 Fig. 4 is a section thru a part of my improved apparatus;

Fig. 5 is a view similar to that of Fig. 2 but illustrating a modified arrangement of certain of the parts;

15 Fig. 6 is a side elevation of Fig. 5 looking from the left; and

Fig. 7 is a section on the line 7—7 of Fig. 5.

20 In the following description it will be assumed that the normal maximum cut-off desired is 50% although I wish it to be distinctly understood that my invention is equally applicable to any other setting such, for example, as a 40% setting or a 60% setting.

25 With my invention the locomotive A can be equipped with any desired type of valve gear B. In the present instance what is well known in the art as a Baker gear is illustrated, but it will not be described in detail

30 because its function and mode of operation are well known to those skilled in the art and, further, because my invention does not involve any improvement therein. Suffice it to say that by means of the reverse gear 11 (which in this instance is shown as a power reverse gear although it need not necessarily be such) with its operating wheel 11a it is possible to adjust the valve gear B so that it will give any desired cut-off

35 for the valves up to the predetermined maximum above referred to. But before entering upon the customary detailed description of the accompanying drawings it is desired to direct attention in the first instance to the

40 diagrammatic Figure 1a which illustrates the essentials of my invention as simply as possible. In this figure I have represented the reverse shaft by the circle at 7, the reverse shaft arm by the line at 6, and the reach rod

45 between the reverse gear 11 and the reverse shaft arm by the line at 10. The line 1 indicates the rod which connects the end of the reverse shaft arm 6 to the reverse yoke 2 of the valve gear structure B, 12 representing

50 the pivot between the arm 6 and the rod 1. In carrying out my invention I make the point 16 where the reach rod 10 is coupled to the reverse shaft arm 6 a sliding connection in the slot 13 so that it may be moved 55 toward or away from the pivot 12.

For normal running conditions I arrange (as will appear in more detail later) to keep the point 16 at the top of the slot 13. The other end of the reach rod 10 is pivoted at 43

65 to the piston rod or cross head of the power

reverse gear 11 and the various parts are so connected or correlated under normal running conditions as to make the position 6' of the reverse shaft arm 6 the position farthest "in the corner", as it is colloquially expressed. But this position is arranged to give only a limited maximum cut-off, say 50%, according to our assumption. However, as explained, with this cut-off it might be impossible to start the locomotive so I provide mechanism (to be described below) 70 for automatically lowering the point 16 to the point 16' in the slot 13. When this takes place, with the point 43 stationary as it will be, the reach rod 10 will assume the position 10', the reverse shaft arm the position 6'', and the rod 1 the position 1', and the valve gear B will then be moved to set the valves for a long cut off, say 70 or 75%, so that the locomotive can be started. As soon as a start is made the point 16 is automatically returned to its upper position in the slot 13 which corresponds to a 50% maximum cut-off (according to our assumption). The description has been for forward running but 80 the operation would be exactly the same in reverse except that the reverse shaft arm would be moved to left of its neutral position 6.

With the foregoing rather brief description and analysis in mind I will now describe the details of my invention in its herein disclosed embodiments reference being made to but one side only of the locomotive since many of the parts are simply duplicated on the other side.

The locomotive A is provided with the customary valve chamber or steam chest 3, cylinder 4 and steam pipe 5.

The reverse shaft arm 6 is formed with a suitable hub portion 6a for surrounding the shaft 7 and is keyed thereto. The shaft in turn is mounted in the bearing 8 which is supported from the bracket structure 9.

The reverse shaft arm 6 is moved by means of the reach rod 10 which can be connected either to the customary reverse lever in the cab of a locomotive or to the power reverse gear 11 as illustrated in the present application. The effective "throw" of the reach rod 10, insofar as its effect upon the valve gear B is concerned, is determined by the point of its connection to the arm 6 and as shown and already briefly described the reach rod 10 is connected to the arm 6 at a point intermediate the connection 12 of the rod 1 at the top and the reverse shaft 7. In other words, for any given amount of movement of the reach rod 10, the effect upon the valve gear B will be less if its connection to the arm 6 be at a point near the pivot 12 than if said connection were at a point near the shaft 7.

I arrange for a variable connection between the rod 10 and the arm 6 by providing

the arm 6 with a slot 13 in which slides a block 14. The end of the reach rod 10 is forked as at 15 so that it can embrace the arm 6 and the block 14.

Under our assumption while the block 14 is in the upper position illustrated in Fig. 2 the maximum stroke of the reach rod 10 under the influence of the power reverse gear 11 will produce only a 50% cut-off. Under these circumstances the arm 6 will assume the position 6' indicated in dot and dash lines in Fig. 2.

However, as above explained and well known in the art, the locomotive will not be able to start in any and all positions of the cranks with such a maximum cut-off. Therefore, in order to start the locomotive I make arrangements for moving the reverse shaft arm 6 from position 6' to the position 6'' in Fig. 2. The details associated with this will now be described. But before going ahead with this it might here be stated that the position 6'' can be made to correspond, for example, to about 70% maximum cut-off, but neither this percentage of cut-off nor that which exists when the lever 6 is in its 6' position, namely, 50% under our assumption, are intended to be the upper and lower limits of my invention. By changing the length of the slot 13 or the height of the arm 6 or in many other ways altering the relation of the parts, any desired cut-offs can be provided for.

Inasmuch as for normal average running conditions it is desired and intended to have only a 50% maximum cut-off, I provide means for holding the block 14 in its upper position as illustrated in Fig. 2. Directly below the block and mounted on the arm 6 so that it will be carried therewith I provide a cylinder 17, the piston 18 of which is connected to the block 14 by its piston rod 19. This piston is a double acting one and fluid pressure, preferably air, can be delivered to either side thru the flexible pipes 20 and 21, the former delivering the pressure to the lower face of the piston and the latter to the upper face as clearly shown in Fig. 3. Certain valve mechanisms indicated as a whole by the character C control the fluid pressure in the manner now to be described.

A slide valve 22 in the casing 23 is normally held in position to exhaust the pressure from the upper side of the piston thru the pipe 21, cavity 24 and exhaust port 25 and to admit pressure to the lower face of the piston thru the pipe 26, valve chamber 27, port 28 and pipe 20, the pipe 26 being connected to any suitable source of air pressure on the locomotive such as the reservoir 29. The valve is moved by means of the piston mechanism 30 which is normally held in its right-hand position (see Fig. 2) by means of the spring 31. The rod 32 of this piston enters the valve chamber 27 and is provided

with the lugs 33 for engaging the valve 22. It also carries a valve member 34 which is adapted to seat against the end wall 35 in order to prevent leakage of air around the stem 32 when the piston 30 is in its right-hand position. A similar valve face 36 is provided at the opposite end of the stem 32 in order to prevent leakage therealong when the piston is in its left-hand position to be described just below.

In this way as long as pressure is supplied to the lower face of the piston 18 the block 14 will be held in its upper position and consequently the effect of any movement of the reach rod 10 will be limited to the maximum cut-off desired—under our assumption 50%.

Let us assume now that it is desired to start the locomotive. With the 50% maximum cut-off this might be impossible in certain positions of the cranks. I therefore arrange that when the reach rod 10 has been manipulated by the engineer to give the 50% maximum cut-off referred to either by means of a hand reverse gear or by means of the power reverse gear 11 illustrated herein, the piston 18 will move the block 14 to its lower position. This action will cause the arm 6, already moved to the position 6', to move still further toward the right to the position 6''. When in the position 6' the head of a bolt 37, carried by the arm 6, will be brought into engagement with the plunger 38 as indicated in dotted lines in Fig. 2. The plunger mechanism will then move downwardly to close the valve 39 and open the valve 40 so that fluid pressure can enter thru the pipe 41 and pass over to the piston 30 thru the port 42. The piston 30 will then move to the left in order to cut off the supply of fluid pressure to the underface of the piston 18 and open the pipe 21 leading to the upper face of the piston 18. This action will immediately pull the block 14 down and with it the end of the reach rod 10, the latter being pivoted at 43 to permit of this motion. The pipe 41 is supplied with fluid pressure from any suitable source on the locomotive such as the reservoir 44.

But the flow of fluid pressure to the pipe 41 is subject to an additional control which forms an important part of my invention and which will now be described.

In the pipe 41 is a valve mechanism indicated as a whole by the character D. By referring to Fig. 4 it will be seen that this mechanism includes a valve 45 which is adapted to be closed by the piston 47 upon accumulation of sufficient pressure thereabove to overcome the resistance of the spring 48 and the pressure of the fluid below the valve 45.

The valve 45 in the absence of sufficient steam pressure is normally in its open position because the entrance to the port 49 leading to the piston 47 is normally closed by the

needle valve 50 held downwardly by the spring 51. (This position does not happen to be the one which is illustrated in Fig. 4.) The needle valve is carried by the diaphragm 52 the under face of which is connected by the pipe 53 to the steam pipe 5. The diaphragm 52 is therefore subject to the live steam pressure going to the steam chests or in other words to the steam chest pressure.

10 At this point, in order to more clearly understand the invention, it is necessary to describe the manner in which a locomotive is started. As is well known in the art the engine throttle is never suddenly opened to 15 its full extent. Instead the throttle is but slightly opened in order to admit a limited amount of steam to the cylinder until the locomotive has taken up the slack of the train and the driving wheels begin to revolve.

20 After the slack has been taken up the engineer may open the throttle to its full extent thereby supplying full steam pressure to the cylinders. The reason for this method of 25 starting a locomotive is because if the throttle were instantly opened wide the locomotive might start forward with a sudden lurch with the result that train couplings would be broken or torn apart or other serious damage occur.

30 The average working pressure, let us assume, is 250 lbs. although higher boiler pressures are now not uncommon. I make the power of the spring 51 sufficient to counter-balance a pressure of approximately 200 lbs.

35 so that it is necessary for the pressure below the piston 52 to rise slightly above that point before the needle valve 50 will be opened and the piston 47 moved downwardly to close the valve 45. In this way I make my improved

40 apparatus directly and automatically responsive or subordinate to steam chest pressure for whenever the pressure in the steam chest is below a certain predetermined point say, for example, the 200 lbs. mentioned, the air

45 pressure can flow past the valve 45 to the mechanism C already described so that the normal maximum 50% cut-off will be increased to say 70 or 75%. This will enable ready starting of the locomotive. But just as

50 soon as the engineman opens the throttle to its full extent as previously described, the pressure will rise above the predetermined point and the air pressure will be shut off thru the pipe 41 and the mechanism C will operate

55 to move the block 14 upwardly and restore the normal 50% limited maximum cut-off.

As will be seen the mechanism C in the embodiment illustrated is subject to two separate controlling devices—the valve D which is in the nature of a pilot device, and the parts 37, 38, 39 and 40 associated with and dependent upon the position of the reverse shaft arm. With this arrangement the mechanism D can perform its function only when the reverse arm 6 is in its 50% maximum cut-off position.

In order to permit motion of the arm 6 to the position 6" the plunger 38 is yieldingly held by the spring 54.

Figs. 5 to 7 inclusive illustrate a modification wherein the operating piston for the reach rod 10 is composed of a larger portion 18a and a smaller portion 18b. Pressure is normally applied at all times to the face of the smaller piston thru the pipe 26a so that the reach rod 10 will be held in the upper position in the slot 13. When the valve 39 is closed and the valve 40 opened by the action of the arm 6 and bolt 37 operating upon the plunger 38, air pressure from the pipe 41 will be admitted to the upper or larger piston 18a and thereby force it downwardly against the pressure on the smaller area of the piston 18b. This will move the reach rod 10 downwardly and force the arm 6 from the position 6' to the position 6" exactly in the manner already described in connection with the other figures. It will be noted in Figs. 5 to 7 inclusive that the cylinder 17a with its pistons 18a and 18b and piston rod 19a are located just back of the point 16 instead of directly under it as in the other figures. This, however, is a mere matter of design and is illustrative of the different ways in which my invention may be embodied.

In conclusion I wish to point out that by omitting the control exercised by the reverse shaft arm 6 (parts 37, 38, 39 and 40) it is possible to make the block 14 directly responsive to variations in the steam chest pressure irrespective of the position of the reverse gear and this might be done, of course, in either forward or backward running of the locomotive. The necessary arrangement of parts for accomplishing this is shown in Fig. 2a. Pipe 41 is vented through a leakage groove 45a, a vent 48a and exhaust ports 55 and 56, while the valve 45 is in its closed position. In this way, whenever the steam chest pressure is below a certain predetermined standard the locomotive will operate at a proportionately longer cut-off for a given setting of the reverse gear. But when the pressure in the steam chest is at or above the predetermined standard the cut-off will be less for a given setting of the reverse gear by the proportion made possible through the use of the variable connection in the slot 13.

A brief summary of the operation will now be given.

In the first place, let us assume that the locomotive is being started in a forward direction from a dead stop and that equipment including the parts 37, 38, 39, and 40 shown in Fig. 2 has been adopted. When the locomotive is standing still the pressure in the steam chest is approximately atmospheric pressure. The engineer first actuates the reverse gear 11 to move the reverse shaft arm 6 to the position 6'. When this position is attained the bolt 37 will depress the plunger

38, close the valve 39, and open the valve 40 so that communication is established between pipe 41 and passageway 42 leading to the right hand face of the piston 30.

Inasmuch as the pressure in the steam chests is atmospheric pressure the needle valve 50 (Fig. 4) will be closed because it requires a pressure upwards of 200 pounds to compress the spring 51 in order to open the valve 50. Under these circumstances there will be no pressure above the piston 47 so that the spring 48 will act to move it upwardly and thereby open the valve 45. Air pressure will then flow from the reservoir 44 through the pipe 41 to the right hand face of the piston 30, and the piston 30 as a consequence will be forced to the left, carrying with it the control valve 22.

When this occurs the air pressure entering the valve chamber 27 through the pipe 26 will be admitted to the pipe 21 leading to the upper side of the piston 18 in the operating cylinder 17. At the same time the pressure below the piston 18 will be exhausted through the pipe 20, cavity 24 in the valve 22, and exhaust port 25. As the piston 18 moves downwardly the block 14, of course, will follow so that the connection between the reach rod 10 and the arm 6 will be shifted to its lower position, and since the point 43 is fixed the effect of this motion will be to force the reverse arm 6 to the position 6''. When this occurs the valve gear B will be actuated by the reach rod 1 to increase the cut-off to a point sufficiently great for effecting starting of the locomotive.

The engineer now cracks his throttle in the manner customary in this art, and in this connection it should be recalled, as previously pointed out, that when the locomotive is being started full boiler pressure is never admitted to the cylinders by suddenly opening the throttle wide. As a matter of fact, the engineer may actually open and close the throttle a slight distance a number of times during the starting process so as to avoid a too sudden building-up of full boiler pressure in the cylinders.

With the parts in the position indicated and the cut-off lengthened as described, there is, of course, at all times direct communication into the cylinders through at least some of the main valve passages. In this way the pressure of steam admitted to the steam chests can always escape into the cylinders and the slack in the train is generally taken up in part at least by a pressure which is less than the full boiler pressure.

During this period and just as long as the pressure admitted to the steam chest and to the cylinder is less than, say, 200 pounds, the valve 45 will remain open and the reverse arm 6 will remain in the position 6''. However, just as soon as the train is well started,

the engineer will, of course, open his throttle wide, at which time the pressure will rise above 200 pounds, compress the spring 51, open the valve 50, depress the piston 47, and close the valve 45, so that the air pressure can no longer reach the piston 30. When this occurs, the block 14, of course, will be returned to its upper position because the pressure on the upper side of the piston 18 will be exhausted through the pipe 21, cavity 24, and exhaust passage 25, and live pressure will be admitted to the lower side of the piston 18 through the pipe 20.

This, of course, will immediately return the reverse arm 6 from the position 6'' to the position 6' and the locomotive will then operate as a limited cut-off locomotive. It will be seen, therefore, that with my improved arrangement it is always possible to start the locomotive because with the arm 6 in the position 6'' the cut-off will be substantially that which is normal or customary in the art and sufficiently long to insure a flow of steam to the cylinders regardless of the position of the cranks. Once a start has been made, the engine will continue to move no matter how quickly the pressure may build up above the limit suggested, viz. 200 pounds, because after a start has been made the locomotive will continue to operate even at a 50% cut-off.

If the parts 37, 38, 39, and 40 are eliminated and the pipe 41 directly connected to the passage 42 shown in Fig. 2a, the operation will be slightly different, as follows: Such an arrangement would place the valve gear at all times under the control of the pressure in the valve chest so that whenever the pressure fell below 200 pounds the block 14 would be lowered from its upper position to its lower position and consequently the valve gear B through the connecting reach rod 1 would be actuated to effect proportionately increased cut-offs throughout the entire range of movement of the reverse gear for either forward or backward movement.

This method of operation is extremely valuable in cases where the boiler pressure for some reason or other has run down considerably because under these circumstances an engineer would automatically secure the benefit of greater cut-offs under conditions where with 50% or other limited cut-off the power of the engine would be materially reduced. To state the matter in other words, the increased cut-off at 200 pounds boiler pressure or less would be about equal to 50% cut-off at 250 pounds boiler pressure, and, as stated, by directly connecting the pipe 41 to the passageway 42, I can modify my device to operate in the manner just described.

I claim:

1. In a locomotive having a cylinder and steam admission means therefor, valve-actuating mechanism, valve-reversing gear hav-

- ing connection thereto constructed to effect less than maximum valve cut-off when in full-gear position, and shiftable means for altering said connection to extend the cut-off for starting.
5. In a locomotive having a cylinder and steam admission means therefor, valve-actuating mechanism, valve-reversing gear having connection thereto constructed to effect less than maximum valve cut-off when in full-gear position, and shiftable means for altering said connection to extend the cut-off for starting, together with a pilot means subject to the pressure of the admitted steam for 10 effecting return of said shiftable means to normal position when the pressure of the admitted steam rises above a pre-determined point.
6. In a locomotive having the usual cranks, 15 the combination of a reverse gear, a valve gear, a connection between said gears including means which is shiftable so as to increase or decrease the cut-off, the normal position of said shiftable means being such as to provide a cut-off which is limited to a point substantially below that which is necessary to start the locomotive, and means for shifting said means so as to give a cut-off which is sufficiently increased to start the locomotive 20 with the cranks in any position.
7. In a locomotive, the combination of a valve gear, a reverse gear, a connection between said gears which is shiftable so as to increase or decrease the cut-off and means 25 for shifting said connection to increase the cut-off when the reverse gear is moved to position for starting the locomotive and to decrease the cut-off when the reverse gear is moved out of starting position.
8. In a steam locomotive, the combination of a locomotive valve gear, a reverse gear connected thereto so that the cut-off is normally limited to a point substantially below the maximum necessary to start the locomotive, 30 and means for changing the connection between the reverse gear and the valve gear so as to give a cut-off which is sufficiently increased to start the locomotive.
9. In a locomotive, the combination of a valve gear, a reverse gear, a shiftable connection between said gears normally giving a cut-off less than that which is necessary to start the locomotive, motor means for shifting said connection to increase the cut-off to 35 a point sufficient to start the locomotive when the reverse gear is in position to start the locomotive, and a pilot device subject to the pressure of the steam being delivered to the locomotive steam chests for causing said motor means to shift said connection to establish said normal cut-off whenever said steam pressure is above a predetermined standard.
10. In a locomotive, the combination of a valve gear, a reverse gear, a shiftable connection between said gears normally giving 40 a cut-off less than that which is necessary to start the locomotive and means for shifting said connection to increase the cut-off when the reverse gear is moved to full gear position for the purpose of starting the locomotive.
11. In a locomotive, the combination of a reverse shaft, a reverse shaft arm, a reach rod for moving said arm, a valve gear, a second reach rod for connecting said arm to said valve gear, a connection between the first reach rod and said arm which is shiftable with respect to its distance from the reverse shaft, and means for moving said connection toward the reverse shaft when the reverse gear is moved to full gear position for the purpose of starting the locomotive.
12. In a locomotive, the combination of a reverse shaft, a reverse shaft arm, a reach rod for moving said arm, a valve gear, a second reach rod for connecting said arm to said valve gear, a connection between the first reach rod and said arm which is shiftable with respect to its distance from the reverse shaft, and means for moving said connection toward the reverse shaft when the reverse gear is moved to full gear position for the purpose of starting the locomotive.
13. In a locomotive, the combination of a reverse shaft, a reverse shaft arm, a reach rod for moving said arm, a valve gear, a second reach rod for connecting said arm to said valve gear, a connection between the first reach rod and said arm which is shiftable with respect to its distance from the reverse shaft, and means for moving said connection inwardly to its lesser distance from the reverse shaft when the reverse shaft arm is moved to full gear position for the purpose of starting the locomotive.
14. In a locomotive, the combination of a valve gear, a pivoted arm for controlling said valve gear, a reach rod for moving said arm having a connection with the arm which is movable with respect to its distance from the pivot, and means for moving said connection closer to the pivot to increase the cut-off when starting the locomotive.
15. In a locomotive, the combination of a valve gear, a pivoted arm for controlling said valve gear, a reach rod for moving said arm having a connection with the arm which is movable with respect to its distance from the pivot, means for moving said connection closer to the pivot to increase the cut-off when starting the locomotive, means for returning said connection to its original position, and a pilot device subject to steam chest pressure for causing said last means to function when said pressure rises above a predetermined standard.
16. In a locomotive, the combination of a valve gear, a pivoted arm for moving said gear, a reach rod having a connection with said arm which is movable with respect to its distance from the pivot, a double acting piston for moving said connection, means normally supplying said piston with fluid pressure to hold the connection in its position farthest from the pivot, a valve for exhausting said first pressure and supplying the piston with pressure for moving the connection to its position closest to the pivot,

fluid pressure actuated means for moving said valve to effect said last mentioned operation, and a normally closed valve for controlling said fluid pressure, said last valve being opened by said arm when said arm is moved to position for starting the locomotive.

13. The combination of a steam locomotive, a valve gear, a power reverse gear, a shiftable actuating connection between the valve gear and the power reverse gear capable of being moved so as to alter the cut-off while the position of the power reverse gear remains the same, the normal position of said actuating connection producing a cut-off which is limited to a point substantially less than that which is necessary to start the locomotive, means for shifting said connection to produce a cut-off which is sufficiently long to start the locomotive when the power reverse gear is moved to full gear position, and means for reestablishing the limited cut-off position when the power reverse gear is retracted from full gear position.

14. The combination of a steam locomotive, a valve gear, a power reverse gear, a shiftable actuating connection between the valve gear and the power reverse gear capable of being moved so as to alter the cut-off while the position of the power reverse gear remains the same, the normal position of said actuating connection producing a cut-off which is limited to a point substantially less than that which is necessary to start the locomotive, means for shifting said connection to produce a cut-off which is sufficiently long to start the locomotive when the power reverse gear is moved to full gear position, and means for reestablishing the limited cut-off position when the power reverse gear is retracted from full gear position, together with pilot means which is subject to the steam chest pressure for preventing the attainment of the aforesaid greater cut-off when the steam chest pressure is above a predetermined standard.

In testimony whereof I have hereunto signed my name.

WILLIAM E. WOODARD.
